CARBURETOR CONSTRUCTION

Filed Sept. 9, 1927

INVENTOR
E. FRISBIE
BY *Munn & Co.*
ATTORNEY

UNITED STATES PATENT OFFICE.

EUGENE FRISBIE, OF HILSDALE, MICHIGAN.

CARBURETOR CONSTRUCTION.

Application filed September 9, 1927. Serial No. 218,517.

My invention relates to improvements in carburetor constructions, and it consists in the combinations, constructions and arrangements herein described and claimed.

5 An object of my invention is to provide a means whereby all leaking or flow of liquid into the carburetor of an internal combustion engine may be stopped.

A further object of my invention is to 10 provide a device of the type described in which this means may be actuated from the instrument board of the automobile.

A further object of my invention is to 15 provide a device of the type described by means of which great damage would be prevented from happening to the automobile should the automobile catch on fire as the supply of gasoline is completely shut off from the carburetor.

20 A further object of my invention is to provide a device of the type described which will also aid in preventing the automobile from being stolen as the automobile could only be driven a short distance until the 25 gasoline in the carburetor is consumed and the automobile would then stop, owing to the fact that the supply of gasoline is shut off from the carburetor.

Other objects and advantages will appear 30 in the following specification, and the novel features of the invention will be particularly pointed out in the appended claim.

My invention is illustrated in the accompanying drawings, forming part of this application, in which

35 Figure 1 is a sectional view of my device as applied to a carburetor, and

Figure 2 is a section along the line 2—2 of Figure 1.

40 In carrying out my invention, I make use of a carburetor 1 having a float 2 and a valve 3 arranged to engage with a valve seat 4 for closing the passage in the supply pipe 5.

45 I provide a housing 6 having a weight 7 movably disposed therein. A resilient rod 8 is rigidly secured to the weight 7 and extends upwardly through the housing 6 and through a flexible tube 9 and an instrument board 10. A button or knob 11 is rigidly secured to the free end of the resilient rod 8.

The housing 6 is disposed in alignment with the valve 3. A spring 12 is disposed in the housing 6 concentric with the resilient 55 rod 8 between the upper end of the housing and the weight 7. A latch member 13 is pivotally secured at 14 to the instrument board 10 for a purpose hereinafter described.

From the foregoing description of the various parts of the device, the operation thereof may be readily understood. The float 2 and valve 3 simulate an ordinary float valve of an ordinary carburetor 1. The float valve is adapted to permit a predetermined 60 amount of gasoline to enter the carburetor through the feed pipe 5. Let us assume that the user wishes to park the car. By moving the locking member 13 to one side about its pivot, the weight 7 may be moved downwardly into engagement with the valve 3 by pressing the knob 11 and by the aid of the spring 12. By forcing the weight 7 downwardly as far as possible, the valve 3 will be forced into engagement with the valve seat 65 4, thus positively closing the passageway in the feed pipe 5. The spring 12 is sufficient to hold the weight 7 in engagement with the valve 3, thus preventing the passage of gasoline into the carburetor. 70

The weight 7 may be removed from the valve 3 by pulling outwardly upon the knob 11 a sufficient distance to allow the locking member 13 to freely move between the knob and the instrument board. It is obvious 75 that carburetors differ in construction. However, in the different carburetors the flow of the gasoline into the carburetors is controlled by valves which are actuated by floats. Therefore, the structure may vary to 80 agree with the various types of carburetors without departing from the spirit and scope of the invention.

It will be understood that my device may be embodied in old carburetors as well as new, and may be attached to the ignition switch, whereby it will be operated automatically.

I claim:

The combination with a carburetor and an instrument board, a feed pipe for said carburetor, and a float valve arranged to vary the amount of liquid passing into said carburetor, of a weight member arranged to

engage with said float valve for actuating said float valve for positively stopping the flow of liquid into said carburetor, a resilient rod having one end secured to said 5 weight member, a knob secured to the other end of said resilient rod, said resilient rod extending through said instrument board,

and a member pivotally mounted upon said instrument board and arranged to be passed beneath said knob for holding said resilient 10 rod outwardly and for holding said weight member away from said valve.

EUGENE FRISBIE.
